205,174
VEHICLE

Richard A. Dinkel, East Lansing, Mich., assignor to American-Mobile Products Corporation, Lansing,
Mich., a corporation of Michigan

Filed Sept. 23, 1965, Ser. No. 87,139

Term of patent 14 years

(Cl. D90—8)

FIG. 1

FIG. 2

FIG. 3

FIG. 4

FIG. 5

I claim:

The ornamental design for a vehicle, as shown and described.
